(57) **CLAIM**

The ornamental design for a wipe with pattern, as shown and described.

DESCRIPTION

The sole FIGURE is a top plan view of a wipe with pattern showing our new design. The broken lines in the drawing define the boundaries of the wipe to which the pattern is applied, and form no part of the claimed design. It is understood that the pattern repeats uniformly throughout the length and width of the design.

1 Claim, 1 Drawing Sheet
